2 SHEETS—SHEET 2.

UNITED STATES PATENT OFFICE.

FRANK HODSON, OF NOKOMIS, ILLINOIS.

SAFETY-CATCH.

1,381,555.

Specification of Letters Patent. Patented June 14, 1921.

Application filed June 20, 1919. Serial No. 305,482.

To all whom it may concern:

Be it known that I, FRANK HODSON, a citizen of the United States, residing at Nokomis, in the county of Montgomery and State of Illinois, have invented certain new and useful Improvements in Safety-Catches, of which the following is a specification.

This invention relates to an attachment for elevators and has for its principal object the production of a safety catch or device which is so constructed as to allow the elevator cage to move vertically, either upwardly or downwardly along its guides when in usual operation, although in the event the lifting cable or chain or other device is accidentally severed or breaks, the device will automatically operate for preventing a fall of the cage.

One practical form of construction and assembly of the present invention will be hereinafter described and is illustrated in the drawings in which:—

Figure 1 is a front elevation of the elevator attachment illustrating the device in use.

Fig. 2 is a transverse vertical section through the device taken at right angles to Fig. 1, illustrating certain operative parts in dotted lines.

Fig. 3 is a fragmentary elevation of a portion of the device illustrating the specific construction of the wedges and co-operative elements thereof.

In the preferred embodiment of the present invention, about to be specifically described, 5 indicates the parallel vertically extending guides of an elevator shaft. In considering the present invention it should be understood that the device is capable of use upon passenger elevators in buildings or upon freight elevators as well as upon the cages used in mine shafts. The bottom 6 of the elevator car has end walls 7 bearing upon the guides 5 and it will be noted that angular brackets 8 are connected to the end walls 7 as shown at 9 and are also connected to the supporting bars 10 which are parallel to each other although spaced apart as shown in Fig. 2. Lifting chains 11 are connected by links 12 to shafts 13 carried by the bars 10 as shown in Figs. 1 and 2. These chains 11 are also connected to a ring 14 to which the lifting cable 15 is connected. Therefore as the lifting cable 15 is wound upon a drum or pulled, it will be noted the chains 11 will lift the

elevator. It should be understood that although a specific form is described any particular form or design of cage or car may be provided without departing from the spirit of the invention, as the novelty does not exist so much in the construction of the cage and car as in the specific safety catch to be hereinafter described. As the cable 15 is unwound it will be noted that the car 65 may move down between the guides 5.

Transversely extending supporting webs 16 are secured upon the upper ends of the walls 12 and are also connected to the brackets 8 as shown in Figs. 1 and 2. Extending parallel to these webs 16 and passing upon the outer side of the guides 5 are cover plates 17. Sector shaped cam blocks 18 are interposed between the webs 16 and plates 17 upon each side of each guide 5 as illustrated clearly in Fig. 3. Retaining elements 19 are passed through the webs 16 and plate 17 as well as through the blocks 18, thus firmly anchoring the blocks in position. The inner edges of the blocks 18 are slanted as shown at 20, thus providing the cam surfaces, which surfaces are near to, although spaced from the side edges of the guides 5.

Operating levers 21 are pivotally mounted upon pins 22, it being noted that the pins 22 are also carried by the webs 16 and plates 17. Thus the levers 21 are pivotally supported, it being noted that the inner ends of the levers extend to points contiguous to the guides 5, although the outer ends of these levers extend outwardly beyond the webs and plates for a considerable distance as shown in Fig. 2.

Wedges 23 are provided, it being noted that the rear edge of each wedge 23 is slanted as shown at 24 while the forward surface thereof is vertical as shown at 25. The upper ends of the wedges 23 are pivoted as indicated at 24 to the inner ends 90 of the levers 21. Accordingly when the outer ends of the levers 21 are swung upwardly, their inner ends will swing downwardly, thus forcing the wedges 23 downwardly. When however the outer ends of the levers are swung downwardly the inner ends will move upwardly, thus lifting the wedges 23 and causing their inclined slanting rear edges 24 to ride across the cam faces 20 of the blocks 18, thus bringing the 100 wedges into binding engagement with the side edges of the guides 5.

Coiled springs 26 have their lower ends fixed upon the walls 7 or other desired part of the elevator, car, or cage as shown at 27, while the upper ends of the springs are 5 connected by yokes 28 to the outer ends of the levers 21, since the yokes are supported upon transversely extending bolts 29. Accordingly, the resiliency of the coiled springs 26 is at all times exerting a pull upon the 10 outer ends of the levers 21. However, auxiliary chains 30 are connected by yokes 31 to the bolts 29 carried by the outer ends of the levers 21, while the upper ends of the chains 30 are connected to the ring 14 carried 15 by the lifting cable 15.

When the device is in use and under normal conditions the chains 11, which of course can be cables, are held in a taut condition as they support the weight of the elevator 20 car or cage. Accordingly, as the cable 15 is wound upwardly or unwound to move downwardly, the elevator car or cage may move upwardly and downwardly along the guides 5 in the usual manner.

25 The manner in which the wedges 23 are reinforced by the blocks 18 will firmly hold the car or cage against side shifting. Under such conditions the taut condition of the chains 30 will cause the outer ends of the levers 21 to be held in raised conditions, thus causing the wedges to be in a lowered condition as shown in dotted lines in Fig. 2 and illustrated in full lines in Fig. 3.

However, if for any reason the cable 35 15 is severed or breaks, or the operating mechanism for lifting the elevator car or cage becomes inoperative or broken, any of which conditions would ordinarily allow the elevator car or cage to fall and the occupants 40 thereof to be injured or freight thereon to be demolished, by use of the present device such serious objections will be overcome. It will be realized that as soon as the cable 15 becomes inoperative for any reason whatever, the normal pull upon the chains will be 45 released thus causing the same to become slack. Instantaneously with such action the coiled springs 26 will be released and due to their tension will immediately swing the 50 outer ends of the levers 21 downwardly with speed and force which action will shift the wedges 23 upwardly as hereinbefore explained. As the wedges ride across the cam faces of the blocks 18 they will be brought 55 into binding engagement with the guides 5, thus causing the wedges to bind firmly upon the guides and thus limit the fall of the elevator car or cage. It is apparent that in the event there is a heavy load in the car or 60 cage the operation of the device may be rendered more efficient, for under such conditions the weight would tend to move the blocks 18 a slight distance further toward

the lower ends of the wedges 23 and thus bind the wedges even in a firmer engagement 65 with the guides 5, whereby the car will be held from falling and as a consequence the occupants thereof or material carried thereon will not be injured, as the car will be suspended until the broken cable or other defective portion has been repaired and the car or cage is again lifted, thus causing the levers to retract the wedges from their binding engagement with the guides, whereupon the elevator car or cage will again be used 75 in proper and usual manner.

It will therefore be seen that a very simple and efficient mechanism has been provided, wherein the safety device is normally held in a set condition, so that in the event 80 the lifting mechanism of the elevator suddenly becomes defective and the car starts to fall, this safety mechanism will automatically operate to grip the usual guides of the elevator shaft whereupon the movement of 85 the car or cage will be limited and the car or cage will be suspended upon the guides 5 as long as necessary, without danger of 90 injury to the occupants or the material carried thereby.

The foregoing description and the drawings have reference to the preferred embodiment of my invention. It is to be understood, however, that I may make such changes in construction and assembly of 95 parts, materials, dimensions, etc., as may prove expedient and fall within the scope of the appended claim.

Having thus fully described my invention, what I claim as new and desire to secure by 100 Letters Patent is:—

In combination with a guide having an elevator car movable therealong and means for raising and lowering the car, a safety device including a supporting web secured 105 to the car and extending across the inner face of the guide, a cover plate extending across the outer face of the guide, cam blocks on opposite sides of the guide and secured between said web and cover plate, wedges disposed between the cam blocks and sides of the guide, a lever pivotally connected to the upper end of each wedge and pivoted between said web and plate, means connecting said levers to said raising and lowering 115 means for normally maintaining said wedges inoperative and spring means connected to said levers and said car for moving the wedges into binding engagement with said guides.

In testimony whereof I affix my signature in presence of two witnesses.

FRANK HODSON.
